1

Genus and species: *Dianthus caryophyllus*.
Variety denomination: 'KLEDP17262'.

**BACKGROUND OF THE NEW PLANT
'KLEDP17262'**

The present invention comprises a new and distinct variety of *Dianthus*, botanically known as *Dianthus caryophyllus*, and hereinafter referred to by the variety name 'KLEDP17262'. 'KLEDP17262' originated from a whole plant mutation from the *Dianthus* parent 'KLEDP14206', also commercially known as OSCAR 'Purple Wings' (U.S. Plant Pat. No. 26,846) in June 2014 in The Netherlands.

In September 2014, 'KLEDP17262' was first vegetatively propagated by vegetative stem cuttings in Stuttgart, Germany and Latina, Italy. 'KLEDP17262' was found to reproduce true to type in successive generations of asexual propagation in Stuttgart, Germany via vegetative stem cuttings.

SUMMARY OF 'KLEDP17262'

The following are the most outstanding and distinguishing characteristics of 'KLEDP17262' when grown under normal horticultural practices in Stuttgart, Germany.

1. Red-purple flowers with lighter red-purple borders; and
2. An upright habit.

DESCRIPTION OF THE PHOTOGRAPH

This new *Dianthus* plant is illustrated by the accompanying photograph of a plant approximately 10-weeks-old and grown in a greenhouse in Stuttgart, Germany. The photograph shows the whole plant, including the flowers and foliage and buds of 'KLEDP17262' and was taken in March 2016 in Stuttgart, Germany. The colors shown are as true as can be reasonably obtained by conventional photographic procedures.

DESCRIPTION OF 'KLEDP17262'

The following detailed descriptions set forth the distinctive characteristics of 'KLEDP17262'. The data which

2

define these characteristics were collected from asexual reproductions carried out in Stuttgart, Germany. Data was collected in April 2018 on 6-month-old plants grown in a plastic greenhouse. Color references are to The R.H.S. Colour Chart of The Royal Horticultural Society of London (R.H.S.), 5th edition (2007).
